UNITED STATES PATENT OFFICE.

ERNEST H. SIPPEL AND NORMAN J. WRIGHT, OF TOLEDO, OHIO, ASSIGNEES, BY MESNE ASSIGNMENTS, TO THE ELECTRIC AUTO-LITE COMPANY, OF TOLEDO, OHIO, A CORPORATION OF OHIO.

INSULATION-SEVERING DEVICE.

Application filed June 4, 1920. Serial No. 386,498.

This invention relates to insulated electric wire and particularly to the severing or parting of the insulation covering the wire, it being an object of our invention to sever or 5 part the insulation in an expeditious manner and without in any way injuring the metal conductor underneath.

Whenever it is necessary to lay bare the conductor of an insulated wire for the purpose of making an electrical connection with another wire or binding post or for attaching a terminal clip to the wire, the insulation covering has been commonly removed or pushed back by first cutting through it 10 by means of a sharp knife or similar tool and then peeling or pushing back the insulation. In quantity production this operation, even though carried on thousands of times per day by an expert operator, is at 15 best slow. Moreover, the wastage is large, particularly where the wire is a cable built up of many fine wires for, unless the utmost care is constantly exercised, the outer strands of the cable will be accidentally severed as 20 well as the insulation.

According to our invention, we bring the insulated wire in contact with a metallic strip heated to a red heat by passing a current of electricity through it and by giving 25 the wire a rotative movement, burn through the insulation and thereby sever it. The ends of the insulation may then be pushed back leaving the bare conductor.

Further objects of this invention relate 30 to economies of manufacture and details of construction as will hereinafter appear from the detailed description to follow. We accomplish the objects of our invention in one instance by the devices and means described 35 in the following specification, but it is evident that the same may be varied widely without departing from the scope of the invention as pointed out in the appended claims. A structure constituting one embodiment of our invention, which may be the preferred, is illustrated in the accompanying drawings forming a part hereof, in which:

Figure 1 is a side elevation of a device involving our invention,

Fig. 2 is a top plan view of the same

showing a piece of insulated wire being held in position on the device,

Fig. 3 is an end elevation, and

Fig. 4 is a sectional view taken on the line 4—4 of Fig. 1.

In the drawings, the same reference numerals refer to similar parts throughout the several views, and the sectional views are taken looking in the direction of the arrows 60 at the ends of the section lines.

Referring to the drawings, a base 5 having a channel 6 supports a block 7 of insulating material, preferably of a refractory nature, such for instance as fire clay. 65 This block 7 is shown held in proper position by four clamping strips 8 screwed to the base 5 and is provided with a longitudinal channel or slot in which rests a hot strip 9. This strip 9 is preferably constructed of 70 suitable resistance metal not readily oxidized and is electrically connected by suitable means, such as screws and washers, with a pair of terminal brackets 10 which are secured to the base 5 and to which are attached the terminals 11 of the current conductors 12. The base 5 is constructed preferably of slate, marble or other suitable insulating material, however, it may, if desired, be made of metal in which case one 80 or both of the terminal brackets 10 should be insulated therefrom. In order to leave the hot strip 9 exposed for operating upon the insulated wire, the block 7 is provided with a V-shaped notch 15. There is also provided a gage 16 which is adjustably secured to a bracket 17 attached to the base 5 by means of which the insulation may be severed at a predetermined distance from one end of the wire. 85

In the use of this device the terminal brackets 10 are connected to a source of current such that the strip 9 will be brought to a dull red heat. The operator then holds the wire, whose insulation is to be severed, 90 against the hot strip with one end against the gage 16 in a manner such as is illustrated by Fig. 2 and rotates the wire. In this figure the operator is shown in the act of severing the insulation on a connector wire 100 19 which has already been provided with a clip 20 at each end. The heat from the hot

strip 9 quickly burns through the insulation as it is rotated by the operator without, in any way, injuring the fine wires of which this connecting wire is ordinarily composed.

Inasmuch as the invention herein disclosed is susceptible of various other embodiments and as various changes might be made in the embodiment set forth, it is to be understood that all matter described above or shown in the accompanying drawing is to be interpreted as illustrative only, and not in a limiting sense.

Having thus described our invention, what we claim as new and desire to secure by Letters Patent, is:

1. In a device of the class described, a support, an insulating unit carried by said support and having an axial groove there-in, and an electrical heating element partially embedded in the bottom of the groove

in said unit and having a thin flat upper edge; said unit being cut away adjacent the center thereof to expose said heating element.

25

2. In a device of the class described, a base member, a bracket at each end of said base member and attached thereto, an insulating member extending between said brackets, means to secure said insulating member to said base member, and an electric heating element having a thin flat upper edge partially embedded in said insulating member and electrically connected to said brackets, said insulating member being cut away at the center to provide access to said heating element.

In testimony whereof, we affix our signatures.

ERNEST H. SIPPEL.
NORMAN J. WRIGHT.
